UNITED STATES PATENT OFFICE

1,921,534

PROPELLER

Bynum B. McCrosky, Oakland, Calif.

Application February 29, 1932. Serial No. 595,724

1 Claim. (Cl. 170—151)

This invention is a propeller and is especially directed to a device which may be adapted to use as a fan or a propeller for use on air craft or water craft.

5 The main object of the invention is to provide a propeller with which the driving force or the blast may be varied as to direction and which is conveniently adjusted and positive in its action.

Another object of the invention is to provide 10 a device as outlined with an especially efficient type of vane which is operable only during a portion of each revolution whereby the propeller to one side of the axis develops full power while the other side offers substantially no resistance.

15 A further object of the invention is to provide a shutter type of vane and automatic means for its operation.

Other objects and advantages of the invention 20 will become apparent as the following description is read on the drawings forming a part of this specification and in which similar reference characters are used to designate similar parts throughout the several views and in which:

Fig. 1 is a side elevation of the invention.

25 Fig. 2 is a front elevation of the invention.

Fig. 3 is a front elevation of the mechanically actuated vane.

Fig. 4 is a section taken on line 4—4 of Fig. 3.

Fig. 5 is a section taken on line 5—5 of Fig. 3.

30 Fig. 6 is a view showing the automatically actuated vane.

Fig. 7 is a diagrammatic view showing the position of the shutters operated as indicated in 35 Figs. 1 and 2, throughout one revolution of the wheel.

Fig. 8 is a fragmentary view showing the shutters open.

Fig. 9 is a sectional elevation of a modification 40 of the invention taken on line 9—9 of Fig. 10.

Fig. 10 is a front elevation of the modification shown in Fig. 9.

The invention consists of a pair of spaced apart 45 wheels 10 and 11, the wheel 10 having inwardly extending hub 12 and wheel 11 having an inwardly extending hub 14, these wheels being rotatably mounted on a crank shaft 15. The crank shaft has one end rotatably supported in a bearing 16, the other end being provided with adjusting means 17 which may consist of a lever, 50 gearing or other suitable means. Hub 13 is rotatably supported in a bearing 18, whereby the device is supported by the crank shaft on one side and by the hub 13 on the other side. The crank 19 is straddled by the hubs 12 and 14.

55 The crank shaft has an eccentric 20 inter-

posed between the bearing 16 and outside of wheel 11. Power is taken from or delivered to the device through the hub 13, suitable gears or pulleys being secured between bearing 18 and lever 17 on the hub 13.

60 Fixedly secured between the wheels 10 and 11 are brackets 21 which are equally spaced about the periphery and extend inwardly as shown, and are provided with two spaced apart pivots 22 and 23. Vanes 24, 25, 26 and 27 each have two 65 pivots spaced apart as at 28 and 29.

A collar 30 is rotatably mounted on the crank 19 and has a pivot 31 for each vane, and connecting rods connect between the pivots 31 and 29 while other rods connect respectively between 70 the pivots 22 and 29, and 23 and 28 respectively.

Secured to the rims of wheels 10 and 11 are 75 equally spaced shutter vanes 32, 33, 34 and 35, each of which consists of a frame having sides 36 and 37 and top 38 and bottom 39. Pivotable between the sides 36 and 37 are a plurality of shutter blades 40, the pivots being indicated at 41. The blades 40 each have an integral cam member 42 provided with a cam slot 43 which is so formed as to actuate the shutters in such manner as to provide 80 the highest efficiency or lowest reaction, these cam members being spaced from the side 36. Interposed between side 36 and cam members 42 is a plate 44 having pins 45 cooperating with cam slots 43 and an outwardly extending pin 46 which 85 is slidable in a vertical slot in the side 36.

The actuating mechanism for the shutter consists of a plunger 47 having outwardly extending pins 48 which engage the pin 46, the plunger being connected to the collar 30 by means of connecting 90 rods 49, the plungers being resiliently cushioned to prevent chatter, and housed with a shell 50 which is suitably secured to the side 36.

A collar 51 is rotatably mounted on the eccentric 20 and has the connecting rods 49 pivoted 95 thereto as indicated at 52.

An automatic shutter vane is indicated in Figs. 6 and 8 and consists of a housing 53 in which a plurality of pairs of shutters are pivoted at 54, the pairs each consisting of blades 55 and 56 provided with pintle sleeves 57 rotatable on the pintles 54 which are secured in the top and bottom 58 of the housing 53. Equalizing lugs 59 prevent excess opening of either blade, and spreaders 60 prevent the blades from coming together 105 too close to prevent air pressure from opening them.

This shutter vane is particularly adapted to the type of propeller shown in Figs. 9 and 10.

The retractable folding vanes 24 to 27 inclu- 110

sive are actuated by the rotation of the wheels 10 and 11 and actuate the wheel by the variation in distance of the vanes from the axis of the wheel. With the wind blowing in the direction indicated by the arrow the pressure on vanes 24 and 26 would be substantially equal but the distance of vane 24 from the axis of the wheel is about twice that of vane 26. By adjusting crankshaft 15 through an angle of one hundred eighty degrees, the direction of rotation of the wheel would be reversed.

With the vanes 32 to 35, rotation of the wheels 10 and 11 cause the shutters 40 to open and close once for each revolution and under the same conditions as outlined for vanes 24 to 27, the shutters are open in vane 34 starting to open in 33, closed in 32 and just completed closing in vane 35.

Referring to Fig. 7, with the wind blowing in the direction of the arrows, the wheel would turn clockwise and there would be practically no resistance at the positions 61, 62, 63, 64 and 65 while the full wind pressure would be available at positions 66, 67 and 68.

By driving the wheel clockwise from an external source of power wind pressure would be created in the direction of the arrows from the lower part of the fan only. The cam slots 43 can be so formed as to provide the exact operation of the blades as required for any particular purpose.

A modification of the shutter vane propeller is shown in Figs. 9 and 10 in which a pair of spaced apart wheels 69 and 70 which have inwardly and outwardly extending hubs 71 and 72 are rotatably mounted in bearings 73 and 74 integral with a base 75.

A crankshaft 76 is rotatably mounted in the hubs 71 and 72 and has affixed at one end, adjusting means which is indicated in the drawings as a sprocket 77 and chain 78 which may be operated by means of a sprocket 79 through worm gear 80 and worm 81 and which will be substantially self-locking in adjusted position.

Rotatably mounted on the crank 82 of crankshaft 76 is a spider 83 having arms equal in number to the number of vanes used.

The automatic shutter vane indicated in Figs.

6 and 8, is particularly adapted to this type of propeller and these shutter vanes are mounted in pairs as shown at 84 and 85 which are respectively pivoted at 86 and 87 and intermediately connected by a pin 88 secured in the inside walls 53 and forming a crank which is pivoted in the ends of the arms on the spider 83.

Driving means such as a pinion or pulley is secured on one of the hub extensions 72.

With the wheel 69—70 driven in the direction indicated by the arrow, and the crankshaft 76 adjusted in the position shown in the drawings, air reaction at the top vane 89 will be in the direction indicated by the arrow in Fig. 6 causing the vanes to separate forming a full reactive surface. At 90 the shutters 55—56 will be idle as there will be no air reaction. At 91 the air reaction will be in the direction indicated by arrow 92 in Figs. 6 and 8, automatically opening the vane with the shutters in the position shown in Fig. 8, the vanes maintaining a position parallel to each other.

By adjusting crankshaft 76 clockwise through ninety degrees, the vanes will all be directed radially to the right as viewed in Fig. 9 and the air reaction will be upward on the right hand vane 100 90 and vanes 89 and 91 will be idle.

Having described an operable method of constructing and using the invention it will be noted that variations in construction and arrangement of parts which are consistent with the appended claim may be resorted to without detracting from the spirit or scope of the invention of sacrificing any of the advantages thereof.

I claim:

In combination with a propeller, a shutter vane comprising a frame, a plurality of shutter blades pivotally mounted in said frame, integral cam members for said blades, and having cam slots formed therein, a plate having projecting pins cooperating with said cam slots, an outwardly projecting pin on said plate operating through a slot in the side of said housing, a plunger cooperating with said pin, and means for operating said plunger coincident with rotation of said propeller.
